(57) **CLAIM**

The ornamental design for a connecting member for table, as shown and described.

DESCRIPTION

FIG. 1 is a perspective view of a connecting member for table showing my new design;

FIG. 2 is a front view thereof; the rear view being a mirror image;

FIG. 3 is a left side view thereof;

FIG. 4 is a right side view thereof;

FIG. 5 is a top plan view thereof;

FIG. 6 is a bottom plan view thereof;

FIG. 7 is a cross-sectional view taken along section line 7-7 of FIG. 5; and,

FIG. 8 is perspective view thereof shown in use.

The broken lines in the drawings represent unclaimed environment only and form no part of claimed design.

1 Claim, 7 Drawing Sheets
